Des. 218,770
Patented Sept. 22, 1970

218,770

HANDLE FOR CULINARY TOOL

Roger L. Kelly, Arlington Heights, Ill., assignor to American Home Products Corporation, New York, N.Y., a corporation of Delaware

Filed Oct. 8, 1969, Ser. No. 19,467

Term of patent 14 years

Int. Cl. D7—99

U.S. Cl. D44—29

FIG. 2

FIG. 3

FIG. 4

FIG. 5

FIG. 6

FIG. 7

FIG. 1 is a top plan view of a handle for a culinary tool showing my new design.

FIG. 2 is a side elevational view thereof.

FIG. 3 is a bottom plan view thereof.

FIG. 4 is a section taken along line 4—4 of FIG. 1.

FIG. 5 is an end elevational view thereof from the left of FIG. 2.

FIG. 6 is an end elevational view thereof from the right of FIG. 2.

FIG. 7 is a section taken along line 7—7 of FIG. 1.

I claim:

The ornamental design for a handle for a culinary tool, as shown.
